UNITED STATES PATENT OFFICE.

JOHN L. DINSMOOR, OF PHILADELPHIA, PENNSYLVANIA.

AUDIBLE-SIGNAL DEVICE.

Application filed August 7, 1917. Serial No. 184,832.

To all whom it may concern:

Be it known that I, JOHN L. DINSMOOR, a citizen of the United States, and a resident of Philadelphia, in the county of Philadelphia and State of Pennsylvania, have invented 5 certain Improvements in Audible-Signal Devices, of which the following is a specification.

This invention relates to certain improvements in audible signal devices and more particularly in that class or type of such devices, especially designed and adapted for use upon automobiles, and the like and which are provided with electrical actuating means and 10 the object of the invention is to provide a signal device of this general character of a simple and comparatively inexpensive nature, and of a compact and durable construction, presenting important advantages for use by 15 reason of the convenience and economy with which it may be manufactured and assembled, and provided with novel and improved electrical actuating means, so constructed and arranged as to permit of dispensing 20 with the necessity for careful or accurate adjustment of its operative parts, and to avoid liability of breakdown or defective 25 operation such as commonly results in such devices as ordinarily constructed, from 30 faulty or impaired adjustment of the parts thereof.

The invention consists in certain novel features of the construction, and combinations and arrangements of the several parts 35 of the improved signal device, whereby certain important advantages are attained, and the device is rendered simpler, less expensive, and otherwise better adapted, and more convenient and effective for use, all as will 40 be hereinafter fully set forth.

The novel features of the invention will be carefully defined in the claims.

In order that my improvements may be the better understood, I will now proceed to 45 describe the invention with reference to the accompanying drawings, wherein—

Figure 1 is a sectional view taken axially through a signal device constructed according to my invention;

50 Figure 2 is a face view of the device;

Figure 3 is a perspective view showing one of the members of the electrical actuating means detached;

Figure 4 is a view similar to Figure 1, but illustrating a slightly different construction of the improved signal device comprised within my present invention, and 55

Figure 5 is another sectional view somewhat similar to Figures 1 and 4 but illustrating still another modified formation of 60 the improved signal device according to my invention.

In these views I have shown my improvements embodied for use in an automobile horn having a vibratory sounding diaphragm but although my present invention presents important advantages for use in signal devices of this particular kind, I do not desire to be understood as restricting myself to this special application of the 70 invention exclusively.

As shown in Figures 1, 2 and 3, the improved automobile horn embodying my invention is provided with a frame or casing 1, herein shown as formed from a cupped metal disk adapted to enclose and protect certain of the operative parts, and having at its forward part an outwardly directed annular flange 2. The forward open portion of this cupped metal disk or casing member is covered by an annular face plate or closure 3, the edge portions of which are herein shown as permanently secured to the marginal flange 2 of said casing member 1 by means of rivets 4, although screws or other securing means may be employed in lieu of such rivets. 5 represents a projector extended from the central part of said face plate or closure 3, to concentrate and direct the sound therefrom in a well known 80 way.

6 represents a diaphragm extended across the casing member 1 and adapted to be set in vibration by electrical actuating means so as to give an audible alarm or signal which is 85 concentrated and directed by the projector 5 in a well known way. Around the edge of the diaphragm is arranged a gasket 7 of greater diameter than the diaphragm, its edge projecting beyond the edge of said dia- 90

phragm and being held at the outer part by means of the rivets 4 or equivalent securing devices between the face plate or closure 3 and the edge flange of the casing. This gasket in the structure shown assures uniform support for the edges of the diaphragm around its entire circumference, so as to avoid buckling or unsymmetrical straining of the latter, whereby a desirable tone of the signal is assured. To assist in centering the diaphragm, so that its edges shall be out of contact with the rivets or equivalent securing means, the gasket is cemented to the diaphragm or, as shown in the drawings, said diaphragm may be provided with an annular corrugation 8 or equivalent projections, engageable within said gasket to center the same and prevent lateral shifting of the diaphragm when the parts of the device are assembled.

As shown, the marginal portion of the diaphragm is unattached except that said marginal portion is clamped between the face plate or closure 3 and the flange 2 of the casing member and marginal part of the diaphragm being thus held in electrical engagement with the casing member 1; in other words, said marginal portion of the diaphragm is not engaged by the rivets 4, or equivalent fasteners, but on contrary is substantially free therefrom. It is to be noted that gaskets 7 is so positioned that it substantially precludes mechanical contact between the marginal part of the diaphragm and the fastening means 4 for the two parts (1, 3) of the casing, although said diaphragm 6 is retained in electrical contact with the casing member 1, as described, and in this connection the annular corrugation 8 of the diaphragm possesses marked utility for the reason that said corrugation presents a bead or shoulder adapted for mechanical contact with one member, 3, of the two part casing in such a manner as to render the diaphragm self-centering within the casing when assembling the several parts, as well as to preclude displacement of said diaphragm in lateral and edgewise directions.

9 represents a solenoid enclosed within the shell or casing, to the member 1 of which it is secured in any preferred manner, as for example, by means of screws or the like which serve to hold the insulating support 10 of the solenoid coil flush upon the flat rear wall of said member 1, as clearly seen in Figure 1. One end of the coil 11 of the solenoid has electrical connection, as shown at 12, with an insulated binding screw 14 upon the shell or casing member 1, whilst the opposite end of such coil has electrical connection with the brass or other metallic sleeve 15 upon which the solenoid coil is wound. This latter connection may be effected readily and conveniently by stripping the end of the wire from which said coil 11

is to be produced, and winding the same in direct contact with said sleeve 15 in the formation of the solenoid.

16 represents a contact plate or member in electrical connection with the sleeve 15, and formed from any suitable conducting material, and 17 represents the core or plunger of the solenoid which is adapted, when the solenoid is energized, to be drawn within the sleeve 12. The extremity of this core or plunger projects beyond the sleeve 15 adjacent to the diaphragm 6, and is provided with a screw or rivet 18 formed from copper or other good conductive non-magnetic material, by preference, which affords a head or shoulder beneath which is engaged a leaf spring 19, centrally perforated for the passage of the shank of such screw or rivet 18, and provided with oppositely projecting resilient arms 20 which, by engagement upon the plate or member 16, assure electrical connection of the latter with the core or plunger and at the same time exert their tension to retain the headed projecting end of said core or plunger normally drawn outwardly from and beyond the sleeve 15 in such position as to contact upon and connect electrically with the central part of the diaphragm except at such time as the solenoid is energized. To assure good electrical connection of the conductive screw or rivet 18 with the diaphragm, the latter is herein shown provided at its central part with a copper or other conductive rivet or contact point 21.

The diaphragm 6 being in electrical connection with the shell or casing member 1, which carries a second binding screw 22, it will be apparent that when the improved signal device is connected in a suitable circuit, and the latter is closed, the current will flow between the binding screws 14 and 22 by way of the connection 12, coil 11, sleeve 15, thence directly or by way of the contact plate 16 and spring 19 to the core or plunger 17, to diaphragm 6 and casing member 1, so as to energize the solenoid and cause its core or plunger to be drawn within its sleeve 15 against the tension of the spring 19 to such an extent as will suffice to withdraw the contact screw or rivet 18 from electrical connection with the contact point 21 upon the diaphragm, and thereby interrupt the current flow, whereupon the solenoid will be de-energized and the spring 19 will operate to project the core or plunger forcibly into renewed contact with the diaphragm, so as to restore the circuit and simultaneously to operate as a hammer or striker for sounding the diaphragm after which, the solenoid, being again energized by the restoration of its circuit, will operate once more to interrupt said circuit by the attraction of the plunger, the rapidly alternating interruptions and restorations of the circuit effected in

this manner giving rise to the audible signal or alarm by reason of the vibrations of the diaphragm caused by the repeated striking of the core or plunger thereon during its reciprocal movement.

In the construction and arrangement of the parts shown it will be evident that the mechanical sounding devices, including the diaphragm 6 and the hammer or plunger 17 also serve as the circuit controlling or interrupter members, whereby not only is a very material and important economy and advantage attained in the production and manufacture of the improved signal devices by reason of dispensing with the necessity for accurate and careful adjustment of the mechanical and electrical contact devices independently of one another, such as is requisite in various other devices of this general character in which the circuit controlling devices are separately formed from the mechanical sounding devices.

It will also be apparent that the structure and arrangement of the parts is such that the spring 19 operates, in the normal de-energized condition of the device, to place the diaphragm under a certain preliminary or initial strain or flexure, by reason of the force with which the core or plunger 17 is pressed thereon, and this is of advantage by reason of assuring improved electrical connection between the diaphragm and said core or plunger, and furthermore, on account of the retention of such electrical connection being assured throughout a longer interval of time, as compared with ordinary interrupting or controlling devices such as are commonly used in other signal devices of this general character, the diaphragm operating by its resilience as a following contact member, whereby a higher degree of efficiency is attained in the operation of the solenoid, calculated to permit the employment of a stronger spring, whose increased tension will assure the delivery of a heavier blow upon the diaphragm by the core or plunger upon its projection.

The structure and arrangement of the electrical actuating means and sounding devices is also of an extremely simple and comparatively inexpensive nature, calculated to permit production of the improved signal devices at a minimum cost by reason of the reduction in the number of parts commonly required for such devices, and the facility and convenience with which such parts may be assembled, it being apparent that when the coil has been secured in the casing member 1, and its electrical connections have been effected, the core or plunger 17 is readily insertible at the open front part of the solenoid and when in place is securely retained therein by the application of the diaphragm across the open front portion of said casing member.

As shown the plunger 17 and spring 19 are free from direct attachment to any of the parts, thus facilitating the assemblage of the several members composing the signal device for the reason that it is only required to place the plunger within the sleeve 15 and so that the end portions of the spring 19 have mechanical and electrical contact with the plate 16. The spring is free from attachment to plate 16, although it contacts electrically therewith in order that current may flow to and through the diaphragm in the manner described, and, further, said spring has mechanical contact with said plate 16 which thus offers mechanically the required resistance to insure the flexure of the spring when the plunger is drawn within the coil and when the reaction of the spring forces the plunger into hammer contact with the diaphragm. As shown, the plunger and the spring attached thereto are free to turn or rotate relatively to the coil, the sleeve and the face plate.

The riveting of the members 1 and 3, whilst not being essential to the invention is, in some instances, a feature of material advantage since it affords a means for preventing tampering with the operative parts and lessens the liability of derangement or deterioration by affording a permanent mounting for the diaphragm and closure for the casing. To facilitate the removal of the rivets in case it should be desirable to have access to the enclosed parts, I have shown the employment of tubular rivets which may readily be punched out and replaced by others after any necessary internal repairs or replacements shall have been effected.

To prevent or lessen deterioration of the electrical contact devices due to sparking, I have shown the employment of a resistance 25 affording a connection between the terminals 14 and 22 in parallel with the solenoid winding 11. This resistance affords a path for the current flow in the coil when the companion parallel partial circuit including the winding 11 is broken after energization of the solenoid, and effectively prevents injurious sparking so as to permit the employment of copper or other similar contacts, and to dispense with the necessity of using silver or other non-oxidizable contacts such as are required in ordinary signal devices of this general type.

From the above description of my improvements it will be seen that the signal or alarm device constructed according to my invention is of an extremely simple and comparatively inexpensive nature, and is particularly well adapted for use by reason of the efficiency of its operation and the freedom from liability of deterioration due to defective or impaired adjustment or oxidation of the sounding or contact devices,

and it will also be obvious from the above description that the device is susceptible of considerable modification without material departure from the principles and spirit of the invention as defined in the appended claims, and for this reason I do not desire to be understood as restricting myself to the precise formation and arrangement of the several parts of the device as herein set forth in carrying out the invention in practice.

For example, although in many cases it may be a feature of material advantage to employ the loosely mounted core or plunger 17 and spring 19, retained in position merely by the application of the diaphragm outside them, by reason of the facility of assemblage and economy in construction afforded thereby, the invention is not limited in this particular, since if desired the construction shown in Figure 4 may be employed, wherein the core or plunger 17 is carried by the spring 19 which latter has an insulated screw support at 19^a upon the plate 16, which is formed as a partition extended across the shell or casing member 1 and supported at its margin upon a flange 16^a thereof. In this form of the device, I have shown both binding screws 14 and 22 insulated, and the conductive diaphragm 6 mounted between insulating gaskets 7, 7^a and having electrical communication with one of said screws.

In other cases, the structure shown in Figure 5 may be employed without departure from the invention. As shown in this view, the casing member 1 co-operates as a contact member with the core or plunger 17 in lieu of the diaphragm, the latter being struck and mechanically actuated to sound the alarm upon the energization of the solenoid instead of upon its de-energization as in the preceding embodiments of the invention, and the retracting spring 19 serving to restore electrical communication between the core or plunger and casing member 1 after the solenoid shall have been de-energized by interruption of the circuit. In this embodiment of the invention, the casing member 1 may be made somewhat resilient at its point of contact with the core or plunger 17, to prolong electrical communication or if preferred, a contact spring may be provided upon such member 1 for this purpose, to assure the desired efficiency of the solenoid. As seen in Figure 5, the diaphragm 6 is mounted between insulating gaskets, as in the structure shown in Figure 4, but it will be apparent that this is not essential, since the end of the plunger which strikes upon the diaphragm may be tipped with a fiber or other insulating block, as indicated at 26 in the drawing.

It will also be apparent that when my improvements are embodied in devices other than that herein shown, as for example in bells or the like, where the member cor-

responding with the diaphragm is not sufficiently resilient to operate as a following contact, a contact spring may be interposed between said member and the plunger having sufficient resilience to prolong electrical communication with the latter to the desired extent. In such cases, the contact spring will preferably be provided with a striker normally slightly out of contact with the bell or equivalent member.

Having thus described my invention, what I claim and desire to secure by Letters Patent is—

1. A signal device having a resilient current carrying sounding diaphragm, a solenoid having at one side an annular contact member in circuit therewith, a current carrying plunger revolubly mounted in the solenoid, adapted to be vibrated upon energization thereof and adapted for electrical connection with the diaphragm to control the solenoid circuit, and a spring connected with the plunger having shiftable connection with the annular contact member for normally holding the plunger pressed upon the diaphragm and operable to place said diaphragm under an initial flexure adapted to prolong electrical connection with the plunger when the solenoid is energized.

2. In a signal device, a current carrying diaphragm, a bushing provided with a face plate, a solenoid the coil of which is wound on the bushing, a plunger movable within the coil and free to center itself magnetically therein, and a spring attached to the plunger, the terminal portions of said spring being in electrical contact with the face plate and said spring and plunger affording a path for the flow of current to the diaphragm.

3. A signal device embodying a flexible diaphragm, a solenoid coil, a current conducting spool for said coil, a plunger co-operating with said diaphragm to act as a hammer thereon, and a current-carrying spring member positioned externally to said coil and spool and fixedly attached to said plunger, said spring member being seated in electrical contact with said spool and the latter acting as a mechanical resistance to the flexure of the spring when the plunger is magnetically attracted by the coil.

4. A signal device embodying a flexible diaphragm, a solenoid coil, a current-conducting spool therefor, a plunger movable within said spool and positioned for electrical contact with said diaphragm substantially centrally thereof, and a current-carrying spring member positioned exteriorly of the spool and seated in electrical contact therewith, said spring member being supported by the plunger and said plunger and its attached spring being free to rotate axially with respect to the coil and the spool.

5. A signal device embodying a flexible diaphragm, a solenoid spool, a plunger mov-

able within the spool and contacting with the diaphragm substantially centrally thereof, a spring positioned exteriorly of the spool and seated thereon and in electrical contact therewith, said spring being attached to the plunger, and an exciting coil wound on the spool with the inner leg of the winding in contact with said spool, said plun-

ger with the attached spring and the spool being in series with the exciting coil and with the diaphragm, whereby the plunger acts on the diaphragm with a hammer blow under the impulse of said spring. 10

In witness whereof I have hereunto signed my name.

JOHN L. DINSMOOR.
